Primary Examiner—Wallace R. Burke**Assistant Examiner**—Freda S. Nunn**Attorney, Agent, or Firm**—McGlew & Tuttle**[57] CLAIM**

The ornamental design for a computer terminal with ergonomic numerical keyboard, as shown and described.

DESCRIPTION

FIG. 1 is a top plan view of a computer terminal with ergonomic numerical keyboard showing my new design;

FIG. 2 is a front elevational view thereof;

FIG. 3 is a side elevational view thereof; and

FIG. 4 is a back elevational view thereof.

FIG.1

FIG.2

FIG.4

FIG.3
